UNITED STATES PATENT OFFICE

ERNST LAUSCHKE, OF CHICAGO, ILLINOIS, ASSIGNOR TO BARNHART BROS. & SPINDLER, OF SAME PLACE.

DESIGN FOR A FONT OF PRINTING-TYPE.

SPECIFICATION forming part of Design No. 17,758, dated October 4, 1887.

Application filed August 8, 1887. Serial No. 246,470. Term of patent 7 years.

To all whom it may concern:

Be it known that I, ERNST LAUSCHKE, a subject of the Emperor of Germany, residing at Chicago, in the county of Cook and State of Illinois, have invented and produced a new and original Design for a Font of Printing-Type, which is set forth and fully described in the following specification, reference being had to the accompanying imprint, which contains a full and exact representation thereof.

This design comprises capitals, figures, dollar-mark, and punctuation-marks. The letters are all formed of solid lines of uniform moderate width and entirely devoid of shade or hair lines, and are marked by the following peculiarities, which distinguish the design:

First. A heavy dot is placed within the circular portions of some letters, as B, C, D, O, P, Q, R, and S, and in the angles or openings of some others, as J, L, T, U, V, and Y. The effect on the printed page will not be altered if these dots are transferred to some other letters. Too great frequency in the use of them produces a dazzling effect; hence I do not use them in all the letters.

Second. Cross-lines, as in A, G, and H, are oblique, and that of G does not cross the end of the body-curve, as in the strict form of that letter it should do, but only extends inward from it, and is of unusual length.

Third. M and W are "unfinished"—that is, the acute angle made by the middle lines does not reach the level of the ends of the side lines, and in both these letters the left hand middle line is produced beyond the acute angle, and a similarly-appearing feature is presented in K, of which the lower oblique line crosses the upper oblique line.

Fourth. In B, P, and R the semicircular bows terminate without reaching the vertical stem, and in B the two bows do not touch. Both these features contribute to make the letters have an open appearance.

Fifth. Open curves, except where a ceriph is usual, terminate in a slight expansion of the

line, which then ends abruptly, and in some cases is concaved across the end. This feature is seen in the terminals of the bows of B, both terminals of C, the upper terminal of G, the lower terminal of J, terminals of the bows of P and R, both terminals of S, terminals of the curves of figures 2, 3, 5, upper terminal of 50 6, lower terminal of 9, upper terminal of the interrogation-point, and both terminals of the 55 dollar-character, \$.

Sixth. All ceriphs, except on vertical lines, are oblique to the lines on which they are placed, as in E, F, G, K, M, W, and character &.

Seventh. Horizontal lines which usually 60 have a drooping terminal, as the top stroke of F, have such terminal oblique and tapering almost to a point and then swelled to a drop, which terminates it. (Seen in E, F, T, and Z and figures 2, 5, and 7.)

Eighth. Full-length curves, as of C, G, O, Q, and S, are swelled slightly just above the middle, and the swell terminates abruptly at the middle point, forming a spur on the inner side. A similar feature is shown in U on its vertical side lines.

I claim—

The design for a font of printing-type herein shown and described, of medium weight, considerably expanded, and of uniform width 75 lines, the letters B, P, and R having their bows of open curves stopping abruptly short of the stem at its middle and joined to the stem at its upper end, all open curves, including said bows, being flaring or expanded at 80 the ends and terminating abruptly without flourish by square-cut or slightly-concave ends, the letters A, H, and G having their cross-strokes oblique, and the letters M and W having their oblique lines shorter than their side 85 lines and one of the oblique lines extended beyond the other, substantially as set forth.

ERNST LAUSCHKE.
